United States Patent Office.

GEORGE W. LANE, OF PLANTSVILLE, CONNECTICUT.

Letters Patent No. 67,889, dated August 20, 1867.

IMPROVEMENT IN HINGES.

The Schedule referred to in these Letters Patent and making part of the same.

TO ALL WHOM IT MAY CONCERN:

Be it known that I, GEORGE W. LANE, of Plantsville, in the county of Hartford, and State of Connecticut, have invented a new Improvement in Hinges; and I do hereby declare the following, when taken in connection with the accompanying drawings and the letters of reference marked thereon, to be a full, clear, and exact description of the same, and which said drawings constitute part of this specification, and represent, in—

Figure 1, a face view of hinge open.

Figure 2, end view of the same.

Figures 3 and 4, face view of the two parts detached; and in

Figures 5 and 6, a section of each of the two said parts.

This invention relates to an improvement in the manner of securing the two parts of the hinge together, and consists in the peculiar construction of the two parts, which are separable when detached from the door, but inseparable when attached to the door or to whatever it is desired to hinge.

In order to the better understanding of my invention, as well as to enable others to construct the same, I will proceed to a description thereof as illustrated in the accompanying drawings.

A is the one part, B is the other part, each provided with screw-holes, and of the form adapted to the purpose for which they are to be used, as in common hinges. The one part, A, is cast with a rounded bar edge, C, and with two or more openings, D, through the plate, close to the bar C, and at those openings the bar C is cylindrical, as seen in fig. 5. The other part, B, is cast with hooks E, corresponding to the openings D in the plate A, the internal diameter of the said hooks being the same as the diameter of the bar C, so as to hook on to the bar C and pass down into the openings D in the plate A, and so that the two parts when hooked together, as seen in figs. 3 and 4, and attached to two things, F and G, they are inseparable, and the two parts may be turned upon the hinge, as in common hinges.

These two parts are cast separately, and thus are produced without other labor than that required in casting and cleaning, and are therefore of the cheapest possible construction; but having thus fully described my invention, what I claim as new and useful, and desire to secure by Letters Patent, is—

The two parts of the hinge, A and B, constructed so as to be attached together and operate in the manner described.

GEORGE W. LANE.
